CLAIM

The ornamental design for the wet/dry shaver, as shown and
described.

DESCRIPTION

FIG. 1 is a front elevational view of the wet/dry shaver
showing my new design;

FIG. 2 is a side elevational view, looking from the left side
of FIG. 1;

FIG. 3 is a bottom plan view thereof;

FIG. 4 is rear elevational view thereof;

FIG. 5 is a side elevational view, looking from the right side
of FIG. 1; and,

FIG. 6 is a top plan view thereof.
